(57) **CLAIM**

The ornamental design for a wiping element, as shown and described.

DESCRIPTION

FIG. 1 is a front, right perspective view of an embodiment of the wiping element showing my new design;

FIG. 2 is a front view thereof, the rear view being a mirror image thereof;

FIG. 3 is a right side view thereof, the left side view being a mirror image thereof;

FIG. 4 is a bottom plan view thereof;

FIG. 5 is an enlarged view taken from area 5 in FIG. 2 thereof;

FIG. 6 is a front, right perspective view of an embodiment of the wiping element showing my new design;

FIG. 7 is a front view thereof, the rear view being a mirror image thereof;

FIG. 8 is a right side view thereof, the left side view being a mirror image thereof;

FIG. 9 is a bottom plan view thereof; and,

FIG. 10 is an enlarged view taken from area 10 in FIG. 7 thereof.

The dash-dash broken lines shown in the Figures depict portions of the wiping element that form no part of the claimed design.

The dash-dot-dash broken lines indicating the boundaries of the enlarged detail view, and the dash-dash broken lines showing the lead lines for the enlarged detail views, form no part of the claimed design.

The separations depicted by the break lines in the Figures indicate an indeterminate length. Any portion of the article between the break lines forms no part of the claimed design.
